UNITED STATES PATENT OFFICE

2,359,362

ENGINE STARTER

Robert H. Hill, Anderson, Ind., assignor to General Motors Corporation, Detroit, Mich., a corporation of Delaware

Application December 30, 1940, Serial No. 372,369

7 Claims. (Cl. 74—7)

This invention relates to apparatus for starting internal combustion engines, more particularly to the type of apparatus disclosed in Dyer Patent 2,141,178 issued December 27, 1938. This patent discloses a friction drive between the engine to be started and the starting motor, said drive comprising a disc or annular flange associated with the engine fly-wheel or other member connected with the engine crank shaft and a pair of driving discs which are engageable with opposite faces of the driven disc. The driving discs are interconnected by helical splines provided by a series of balls located in helical races provided by parts connected with these discs. Both driving discs are connected with the motor armature shaft through longitudinal splines. By manual means, both of the driving discs are moved into engagement with the driven disc and the motor switch is closed. Rotation of the motor shaft forces the driving discs against the driven disc with pressure sufficient for driving engagement between the motor and driven disc whereby the motor will crank the engine. When the engine becomes self operative, the pressure between the driving discs and the driven disc is automatically relieved so that the engine will not drive the motor.

It is an object of the present invention to improve the coaction between the driving discs so that the relative movement between them in both directions takes place with greater freedom than heretofore. To accomplish this object, I provide an endless track for the balls which cooperate with the helical races of the parts which provide the driving discs. This endless track includes the helical bearing races themselves and also an outside portion connected with the ends of the active portions of the helical races. The balls are free to pass from the helical races into the outside path and return again to the helical races without the resistance which might be encountered in the Dyer construction wherein the bearing races have closed ends.

Another object of the invention pertains to the connection between the driving discs and the driven disc provided by the flywheel. It is known, with respect to any engine starter which drives through the engine flywheel, that the starting motor operated part, pinion gear or friction member, will first engage the flywheel at one of several portions. For a six cylinder 4-cycle engine, there are three portions; for an eight cylinder engine, there are four. Due to the shock of engagement accompanied by the first appli-

cation of cranking power, these portions are subject to greater wear than other parts of the flywheel gear or friction disc. In the type of friction drive disclosed herein, the unit pressure between the driving and driven discs is very high. After many thousands of starting operations, the first engaged portions of the flywheel flange become perceptibly worn. I aim to reduce this wear by providing the flywheel flange with a resilient construction obtained by a deep circumferential groove in the flange separating the two driving-disc-engaging portions of the flange. It is intended that these portions shall yield to take up the shock of driving engagement due to the operation of the starting motor.

Further objects and advantages of the present invention will be apparent from the following description, reference being had to the accompanying drawings wherein a preferred embodiment of one form of the present invention is clearly shown.

In the drawings:

Fig. 1 is a side view partly in section showing a preferred embodiment of the invention in its normal condition.

Fig. 2 is a wiring diagram thereof.

Fig. 3 is a fragmentary longitudinal sectional view of the starting apparatus.

Figs. 4, 5 and 6 are sectional views taken respectively on the lines 4—4, 5—5 and 6—6 of Fig. 3.

Fig. 7 is a perspective view of sleeve 42.

Fig. 8 is a perspective view of driving disc 34 and parts mounted thereon.

Fig. 9 is a perspective view of driving disc 33 provided by tubular shaft 30.

Fig. 10 is a sectional view on the line 10—10 of Fig. 11.

Fig. 11 is an assembly of the two driving disc members, the outer one being shown in phantom by dot-dash lines.

Figs. 12, 13 and 14 are diagrammatic views similar to Fig. 3 but showing the mechanism in different positions of operation.

The motor 20 for starting the internal combustion engine is preferably an electric motor comprising field frame 21 associated with an end frame 22 and a housing 23 which carry bearings 24 and 25, respectively, for the motor armature shaft 26 which carries an armature 27.

Referring now particularly to Figs. 3 to 7 the shaft 26 carries a tubular shaft 30 which is splined at 31 to the shaft 26 so that the tubular shaft 30 is at all times drivingly connected with the shaft 26 but may slide thereon to a limited

extent. The tubular shaft 30 is urged against the end of the bearing 25 by spring 32 which surrounds the armature shaft 26 and which is located between the armature 27 and the left hand end of the tubular shaft 30.

The shaft 30 carries driving disc 33 and driving disc 34 adapted to move into engagement with and to drive a driven disc 35 having a circumferential groove 35a and connected with the flywheel of the engine to be started. The driving discs 33, 34 are so connected with each other that, after the driving discs have been moved against the driven disc 35, rotation of the shaft 30 by the motor will cause the driving discs to be pressed against the driven disc with pressure sufficient for engine starting purposes and that, after the engine has become self operative, the pressure between the driving discs and driven disc will be relieved so that the engine will not drive the starting motor while the engine is self operative. The driving disc 34 is connected with shaft 30 (providing disc 33) through a screw thread or helical spline connection which is provided by a plurality of balls 38 occupying mating helical grooves 39 and 40 provided respectively by the shaft 30 and the tubular extension of driving disc 34.

The discs 33 and 34 are caused to engage driven disc 35 and the starting motor switch is closed by manually operated means, to be described later. Rotation of the motor armature shaft 26 will cause the driving discs to be wedged against the driven disc with a pressure sufficient for engine starting purposes. After the engine becomes self operative and the driven disc 35 attempts to rotate the driving discs 33 and 34 faster than they can be rotated by the starting motor, the driving pressure between the driving discs and the driven disc will be relieved so that the engine cannot drive the starting motor at excessive speed. These functions take place due to the helical spline connection between the driving disc while both are being driven by the starting motor. The embodiment of the present invention includes a means independent of the starting motor for causing the driving discs 33 and 34 to be moved into engagement with the driven disc 35 before the starting motor operates. This means for causing a preliminary engagement of the driving discs with the driven disc will now be described.

The disc 34 has its tubular extension provided exteriorly with a plurality of helical splines 41 adapted to be engaged by the internally splined flange 42 of a sleeve 43 which is supported by a disc 44 fastened to the left end portion of shaft 30. Disc 44 is provided with recesses 44a for receiving tangs 36a of a washer 36 having also tangs 36b received by notches 30a in tubular shaft 30. A nut 37 threaded on shaft 30 clamps washer 36 against disc 44, and the latter against a shoulder 30c of shaft 30. Thus the disc 44 is drivingly connected with shaft 30. Disc 44 has tongues 47 received by a longitudinal groove 48 of sleeve 43. Sleeve 43 is thereby longitudinally splined to the shaft 30. Due to the great mass of parts connected with the shaft 30 including the armature shaft 26 and the armature 27, the shaft 30 tends to remain stationary as the sleeve 43 is moved longitudinally. Hence, the sleeve 43 may move longitudinally without rotating substantially. The pitch of the splines 41 formed on the extension of disc 34 is such that, as the sleeve 43 is moved toward the left from its position shown in Fig. 3, the 75

disc 34 will rotate relative to the shaft 30 in a direction such as to cause the disc 34 to move into engagement with the disc 35.

In order that the sleeve 43 may be moved toward the left from its position shown in Fig. 3 it is provided with an external flange 49 for receiving the ends 50 of a bifurcated lever 70 having at its upper end an elongated notch 71 which receives a pin 72 carried by bifurcated bracket 73 integral with an L-shaped bracket 74 attached to the frame 75a of a solenoid 75 mounted upon the motor frame 21. A spring 76 surrounds a stud 77 attached to the bracket 73 and urges the upper end of the lever 70 against the pin 72. 15 The lever 70 is actuated electromagnetically by means which will now be described with reference to Fig. 2. As shown diagrammatically in Fig. 2, magnet frame 75a encloses electromagnet windings 80 and 81 surrounding a movable solenoid armature 82 guided by the magnet frame 75a for sliding movement toward a stationary core 83 which is located in the magnetic circuit of the electromagnet. The armature 82 is connected by a link 84 with the lever 70. Armature 82 is associated with a rod 85 upon which is mounted a non-conducting collar 86 yielding urged by spring 87 against a shoulder 88, the spring 87 being confined between the collar 86 and a washer 89 held from moving toward the right by a pin 90. A spring 91 located between a stationary part 92 and the rod 85 normally maintains the rod 85 and the armature 82 in the normal position as shown in Fig. 2.

The collar 86 carries a movable switch contact 95 adapted to engage with contacts 96 and 97 of the starting motor switch. Contact 96 is connected by wire 98 with a battery 99 grounded at 99a. Contact 97 is connected with the starting motor 20 which is grounded. Contact 96 is 35 connected with starter solenoid relay 100 having a core 101 surrounded by coil 102 and having an armature 103 attached by a spring hinge 104 to a metal bracket 105 connected with contact 106. Armature 103 carries a contact 106 for engaging a contact 107 connected by wire 108 with terminal 79 of solenoid 75. Terminal 79 is connected with windings 80 and 81, 81 being connected with contact 97 and 80 being rounded at 108.

The circuit of relay coil 102 includes battery 99, armature 109, wire 123, ignition switch 110, switch 111 (closed by the automobile accelerator pedal and opened by engine intake suction when the engine becomes self-operative), and a switch responsive to generator action and comprising contacts 112 and 113. Contact 113, which is grounded, is insulatingly supported by the armature 114 of reverse current relay 115 for connecting the engine driven generator 130 with battery 99. Armature 114 is connected by spring hinge 117 with magnet frame 116 supporting a core 118 surrounded by series coil 119 and voltage coil 120. When the generator is charging the battery the contact 121 of armature 114 engages contact 122 (connected with wire 123) and contact 113 is separated from contact 112. The control apparatus associated with lever 70 causes the driving discs 33 and 34 to be moved into engagement with the driven disc 35 before operating the starting motor 20.

The manner in which the driving discs are caused to engage the driven discs will now be described particularly with respect to Figs. 12, 13 and 14. To start the engine the operator closes the ignition switch 110 and presses the acceler-

ator pedal to close switch 111 and thus connect coil 102 of solenoid relay 100 with battery 99. Relay contacts 106 and 107 close and battery 99 is connected with the windings 80 and 81 of solenoid 15. The armature 82 will move toward the left thereby causing the lever 70 to move to swing toward the left in a clock-wise direction around its pivot 72. During the movement of the lever 70 the contact 95 will be moving toward contacts 96 and 97; but, before engagement of these contacts actually occurs, the driving discs 33 and 34 will be brought into engagement with the driven disc 35 in a manner which will be apparent from a consideration of Figs. 12, 13 and 14.

As lever 70 moves toward the left the entire drive assembly will be moved bodily toward the left from the position shown in Fig. 12 to that shown in Fig. 13 thereby causing the driving disc 33 to engage the driven disc 35. This movement of the drive assembly is resisted by the spring 32 which normally holds the shaft 30 against the bearing 25. Further movement of the lever 70 toward the left causes the sleeve 43 to move to the left relative to the driving disc sleeve 40 thereby causing the driving disc 34 to be rotated in such direction relative to the shaft 30 that the disc 34 will be moved from its position shown in Fig. 13 to that shown in Fig. 14 wherein said disc 34 engages the driven disc 35. The driving discs have now completed their preliminary movements into engagement with the driven discs. Hence the starter drive has been pre-conditioned for operation by the electric motor. After the driving discs have completed their preliminary movement the lower end of the lever 70 cannot move any further toward the left.

Continued motion of the solenoid armature 82 toward the left to close contacts 95, 96 and 97 may take place by reason of the fact that there is lost motion between the upper end of the lever 70 and the pivot bearing 72. Just before these contacts are closed, the spring 76 is held by the solenoid armature 82 under compression, so that yielding pressure is applied between end 50 of lever 70 and the sleeve flange 44. Therefore, it is only after the driving discs have been brought into engagement with the driven discs under yielding pressure that the motor switch contact 95 is caused to engage the stationary contacts 96 and 97. When this occurs the motor 20 operates to turn the shaft 26. The winding 81 is then short circuited and winding 80 only is effective to hold the motor switch closed. Winding 80 comprises preferably a large number of turns of fine wire and winding 81 fewer turns of coarser wire. Both windings are required to effect movement of the armature 82 initially toward the core 83 but winding 80 only is required to maintain the armature 82 in its attracted position. The starting motor then will operate to cause the shaft 26 to rotate in a clockwise direction as viewed looking in the direction of arrow 60 of Fig. 12. At the instant the motor starts to turn the shaft 26, the driving discs 33 and 34 being then in engagement with the driven disc 35, the first action is to increase the pressure between the driving discs and the driven discs due to the helical spline connection between the driving discs.

Thus in response to the operation of the electric motor in turning the shaft 26 the driving discs 33 and 34 are caused to press against the driven disc 35 with pressure sufficient to insure a driving engagement between the electric motor and the engine for engine starting purposes.

Hence the electric motor is drivingly connected with the engine and will start the latter. This driving engagement has been effected noiselessly due to the fact that means independent of the motor have been employed for moving the driving discs against the driven disc before the motor is connected with the current source. Then when the motor is caused to operate it produces noiselessly a pressure between the driving and driven discs sufficient for engine starting purposes.

When the engine becomes self operative and attains a speed such that the linear speed of the driven disc 35 as effected by the engine exceeds the linear speed of the driving discs 33 and 34 as effected by the starting motor, driving engagement between the driving and driven discs of the starter drive is automatically released. This is accomplished that due to the fact that as the driven disc 35 tends to run ahead of the driving discs 33 and 34 these driving discs tend to unscrew themselves from engagement with the driven disc 35. After the engine starts the solenoid 15 is automatically deenergized by the opening of the automatic engine-suction responsive switch 111 and by the separation of contacts 112 and 113 when relay 115 closes its contacts 121 and 122 to connect generator 130 with battery 99. The spring 91 is then released to effect movement of the parts 85, 82, 84 and 70 toward the right as viewed in Fig. 2. The spring 76 will also be released so as to move the upper end of the lever 70 toward the right returning it to its normal position. In this way the engine starter drive parts are restored to normal position as shown in Figs. 1, 2, 3 and 12.

The ends 50 of lever 70 bear yieldingly upon the sleeve flange 49 and the internal flange 42 of sleeve 43 will bear yieldingly against the helical splines 41 of the tubular extension of driving disc 34. Therefore, since the sleeve 43 is yieldingly urged toward the left the driving disc 33 will be yieldingly urged against the driven disc 35; and, since the driving disc 34 is caused to rotate by the sleeve 43 under the action of yielding pressure, the driving disc 34 will be yieldingly pressed against the driven disc 35. Therefore both driving discs are urged by means independent of the motor against the driven disc with yielding pressure. This is desirable for the purpose of compensating for wear of the friction surfaces of the driving and driven discs. There is another purpose which is important. If the engine should make a weak or false start and fail to attain a speed sufficient to insure self operation, the spring 76, being then held under pressure greater than normal by the electromagnet, an actuating force is thereby stored in the spring 76 which tends to maintain the preliminary contact between the driving discs and the driven disc so that, if there is any tendency to relieve pressure between the driving and driven discs during a false or weak start of the engine, this tendency will be counteracted by the tendency of the spring 76 to urge the driving discs almost instantaneously back into cooperative relation with the driven discs. In other words, the spring 76 forms a function analogous to that performed in the conventional one way or overrunning clutch by the springs which are provided each for urging a clutch roller into wedging engagement between the clutch cam and the clutch shell. Thus when the engine attempts to start on its own power and tends to release the driving engagement between the driving and driven discs and then fails to at-

tain a speed sufficient to maintain self operation, the starting motor drive is at all times ready to pick up the load of cranking the engine instantaneously.

The electromagnetic means which operates independent of the motor to cause the driving discs to be pressed against the driven discs before the motor is operated is not only a convenient means for preconditioning the starter drive but is one which is well adapted to cooperate with the starter drive of this type. It requires a relatively small force to move the driving disc 33 from its position shown in Fig. 12 to that shown in Fig. 13 where it engages the driven disc 35 and it requires a substantially greater force to move the driving disc 34 into engagement with the driven disc 35 and to effect compression of spring 76 beyond its normal state of compression. The electromagnetic device is well adapted to provide the actuating forces which are required. At first the attraction upon the solenoid armature 82 is relatively small but the force required to move the driving disc 33 toward the left is relatively small. As the solenoid armature 82 approaches the core 83 the attraction increases greatly to give the necessarily greater force required to move the driving disc 34 against the driven disc 35 and to compress the spring 76 beyond its initial state. It is also necessary that the starter switch contact 95 be pressed against the stationary contacts 96 and 97 with a pressure sufficient to insure a good electrical contact. The electromagnet is also well adapted to give this final pressure which is needed between the starter contacts in the starter switch. During final movement of the solenoid armature 82 toward the left when the air gap between the armature and core is closing up the pull upon the armature increases tremendously and is sufficient not only to effect the desired movements of the engine starter drive but also to compress the spring 87 beyond its initial state of compression and to force movable contact 95 firmly against the stationary contacts 96 and 97.

The electromagnet is so constructed as to effect a pull on the armature 82 sufficient to make good electrical contact between the contacts in the starter switch. The magnetic pull required for closing the switch properly is greater than that sufficient for preconditioning the engine starter drive prior to actual operation of the motor.

As undue pressure between the driving discs and the driven disc prior to operation of the motor is as undesirable as insufficient pressure, the spring 76 operates while the motor switch is closed to limit the force which can be applied by the electromagnet to the shifting lever 70. The spring 76 is so designed that, upon being deflected a certain distance by the armature 82 when closing the motor switch, the spring will exert the proper force upon the lever 70 tending to rotate it clockwise about its pivotal connection with the link 84. In this way the spring 76 operates not only as a spring exerting yielding pressure upon the shifting collar flange 49 for the purposes herein specified but spring 76 operates also as a means for limiting the amount of pressure which can be effected by the electromagnet.

As relative movement between the driving discs 33 and 34 must take place with the greatest possible freedom, if the ultimate in reliability is to be attained, the helical races 39 and 40 for the balls 38 do not terminate in closed ends as in

the Dyer patent but are in communication with an outer track, thereby providing an endless race for the balls. A sleeve 50a is press-fitted over the member 34 and against a shoulder 34a thereof and is attached to said member by a pin 51. To the member 34 (Fig. 10) is attached a scoop 52 by welding at 53 to direct the balls 38 from races 39 and 40 into a straight passage 54 leading into a helical passage 55 provided by sleeve 50a. The passage 55 is enclosed by a tube 56 pressed around sleeve 50a. The right end (Fig. 11) of helical passage 55 is connected by straight passage 57 with the races 39 and 40. A scoop 58 (Fig. 10) similar to scoop 52 directs the balls 38 from races 39 and 40 into passage 57. As the scoops 52 and 58 project inwardly from part 34, it is necessary to provide part 30 with clearance notches 30b (Fig. 11) in order that part 34 may be assembled with part 30 before the balls 38 are added. The balls 38 are then assembled into the endless track and the tube 56 is pressed around the part 50a.

The driven disc 35 is divided by annular groove 35a into two flexible annular flanges which yield under the pressure applied by driving discs 33 and 34 and thus take up all of the shock of engagement by the driving discs and substantially reduce wear on these discs.

While the embodiment of the present invention as herein disclosed constitutes a preferred form, it is to be understood that other forms might be adopted, all coming within the scope of the claims which follow.

What is claimed is as follows:

1. An engine starter drive comprising aligned discs located on opposite sides of a driven disc provided by a flange on the flywheel of the engine to be started and movable axially into engagement therewith, a starting motor, a longitudinally movable shaft driven thereby and connected with the discs, a helical spline connection between the discs comprising balls located in helical races provided by elements associated with the discs and an outer track provided by a member associated with one of the discs and communicating with the ends of the active portions of the helical races.

2. An engine starter drive comprising aligned discs located on opposite sides of a drive disc provided by a flange on the flywheel of the engine to be started, said flange being divided by an annular groove in order to provide flexibility, means for causing the discs to move axially into engagement with the flywheel flange, a starting motor for driving the discs, and means interconnecting the discs and responsive to the turning of the discs by the motor for causing the discs to grip the flange with pressure sufficient for engine cranking purposes, the split flange yielding under said pressure thereby reducing wear of the flange especially where the driving discs first engage it.

3. An engine starter drive comprising a plurality of driving discs positioned on opposite sides of a driven disc provided by a flange formed on the flywheel of the engine, a starting motor having a driving shaft for operating the driving discs, means for effecting engagement of the driving discs with the driven disc and enabling the operation of said driving discs by the starting motor, said means including a plurality of sleeves carried by the motor shaft and supporting the driving discs, said sleeves being relatively movable longitudinally and rotatively, a helical spline connection between the sleeves comprising a hel-

ical ball race formed in the sleeves and containing a plurality of balls and means to form an endless track for said balls comprising a passage connecting with said ball race at separated points, so that the balls can move around the endless track and friction is reduced.

4. An engine starter drive comprising a plurality of driving discs positioned on opposite sides of a driven disc provided by a flange formed on the flywheel of the engine, a starting motor having a driving shaft for operating the driving discs, means for effecting engagement of the driving discs with the driven disc and enabling the operation of said driving discs by the starting motor, said means including a plurality of sleeves carried by the motor shaft and supporting the driving discs, said sleeves being relatively movable longitudinally and rotatively, a helical spline connection between the sleeves comprising a helical ball race formed in the sleeves and containing a plurality of balls, a member carried by one of said sleeves and having a channel formed therein which is arranged to connect with said ball race at separated points, so as to form an endless track through which the balls may move continuously.

5. An engine starter drive comprising a plurality of driving discs positioned on opposite sides of a driven disc provided by a flange formed on the flywheel of the engine, a starting motor having a driving shaft for operating the driving discs, means for effecting engagement of the driving discs with the driven disc and enabling the operation of said driving discs by the starting motor, said means including a plurality of sleeves carried by the motor shaft and supporting the driving discs, said sleeves being relatively movable longitudinally and rotatively, a helical spline connection between the sleeves comprising a helical ball race formed in the sleeves and containing a plurality of balls, a member carried by one of said sleeves and having a channel formed therein which is arranged to connect with said ball race at separated points, so as to form an endless track through which the balls may move

continuously, and guiding means associated with the ball race to guide said balls into the channel formed in said member.

6. An engine starter drive comprising a plurality of driving discs positioned on opposite sides of a driven disc provided by a flange formed on the flywheel of the engine, a starting motor having a driving shaft for operating the driving discs, means for effecting engagement of the driving discs with the driven disc and enabling the operation of said driving discs by the starting motor, said means including a plurality of concentric and adjacent sleeves carried by the motor shaft and supporting the driving discs, said sleeves being relatively movable longitudinally and rotatively, a helical spline connection between the sleeves comprising a helical ball race formed in the adjacent surfaces of the said sleeves and containing a plurality of balls, a sleeve supported on the outside sleeve of said concentric sleeve and having a channel formed therein which is arranged to connect with said ball race at separated points so as to form an endless track through which the balls may move continuously, in order to reduce friction.

7. An engine starter drive comprising a plurality of driving discs positioned on opposite sides of a driven disc provided by a flange formed on the flywheel of the engine, a starting motor having a driving shaft for operating the driving discs, means for effecting movement of said driving discs into engagement with said driven disc and for operating said driving discs to rotate the driven disc after engagement of the driving discs therewith, said driven disc being divided into two parts by an annular groove in order to prevent damage to the surface of said driven disc by repeated engagement of the driving discs therewith, said annular groove permitting movement of the parts of said driven disc toward each other when engaged by the driving discs so as to prevent damage to the surface with which the driving discs engage.

ROBERT H. HILL.
